US00D979417S

(12) **United States Design Patent** (10) Patent No.: **US D979,417 S**
(45) Date of Patent: **** Feb. 28, 2023**

(54) **BOTTLE**

(71) Applicant: **HAMADA SYUZOU CO., LTD.**,
Kagoshima-prefecture (JP)

(72) Inventor: **Kenji Nakato**, Tokyo (JP)

(73) Assignee: **HAMADA SYUZOU CO., LTD.**,
Kagoshima-prefecture (JP)

(**) Term: **15 Years**

(21) Appl. No.: **35/512,644**

(22) Filed: **Sep. 9, 2021**

(80) **Hague Agreement Data**

Int. Filing Date: **Sep. 9, 2021**

Int. Reg. No.: **DM/216223**

Int. Reg. Date: **Sep. 9, 2021**

Int. Reg. Pub. Date: **Sep. 24, 2021**

(30) **Foreign Application Priority Data**

May 17, 2021 (JP) ..... 2021-010247 D
